UNITED STATES PATENT OFFICE.

HENRY G. McCOME, OF NEW YORK, N. Y.

HEADLIGHT.

1,255,325.

Specification of Letters Patent. Patented Feb. 5, 1918.

Application filed August 30, 1917. Serial No. 189,014.

To all whom it may concern:

Be it known that I, HENRY G. McCOMBE, a citizen of the United States, and a resident of the borough of Manhattan, city, county 5 and State of New York, have invented a certain new and useful Improvement in Headlights, of which the following is a specification.

My invention relates to headlights for 10 automobiles and more particularly to a headlight capable of tilting vertically in order that the glare of the light will not be thrown in the face of one traveling in the opposite direction to that of the car on 15 which the headlight is carried while at the same time the full volume of the light is kept on the road in order that the eyes of the driver will not be affected by any change in brilliancy of the illumination.

20 The danger from the blinding glare of a powerful headlight on the driver of an approaching car is well understood and many States and municipalities have passed laws prohibiting the use of headlights unless 25 they are equipped with lenses which will break up the direct glare of the reflected light.

Most cars at the present time are equipped with attachments by means of which the 30 driver may dim his lights when approaching another car traveling in the opposite direction. This practice is fraught with as much danger as when the dimmer is not used for the reason that while the driver has dimmed his light to make it possible for the approaching driver to see clearly he has so diminished his own light that before his eyes become accustomed to the change a serious accident may occur.

40 The object of my invention is to produce a dirigible headlight operable at the will of the driver and by means of which the axis of the beam may be lowered so that the zone of intense illumination will be below the 45 eyes of an approaching driver but the roadway in the vicinity of the car will be as brilliantly lighted as before.

Another object is the production of such a headlight in which the parts may be positively locked in either position.

50 A further object is to produce a dirigible headlight which may be operated with the expenditure of the minimum of energy on the part of the driver whereby he may have 55 complete control of his car at all times.

I have illustrated one embodiment of my

invention in the accompanying drawings in which like parts in all of the several figures are designated by similar reference characters, and in which— 60

Figure 1 is a top plan view of a headlight embodying my invention, the casing being shown in section.

Fig. 2 is a vertical, longitudinal section on the line 2—2 of Fig. 1. 65

Fig. 3 is a horizontal section of the operating mechanism, and

Fig. 4 is a diagrammatic view showing the wiring.

In carrying out my invention I provide a 70 casing 1 which may be of any desired construction and which may be carried on an automobile in any known manner. The front of the casing is covered by a glass 2 to prevent the entrance of dirt and moisture. 75

Within the casing is disposed the usual parabolic reflector 3 which carries a source of illumination, which in the present embodiment of the invention is an electric bulb 4. The wiring for the bulb may be let into 80 the casing through a nipple 5.

Surrounding the front or open end of the reflector is an annulus 6 which on diametrically opposite sides has trunnions 7, 7 which engage bearings 8, 8 carried by the casing 1. 85 The trunnions and bearings are disposed horizontally relatively to the car so that the reflector may be rocked to raise and lower its focal axis so that the beam of light may be directed ahead horizontally or be caused 90 to strike the roadway close to the front of the car.

The mechanism for moving the reflector consists of a solenoid 9 supported on the inside of the casing 1 and having its core 10 95 connected to the ring or annulus 6 at a point perpendicular to the axis of the trunnions 7, 7 so that when the solenoid is energized the core will be attracted and the reflector rocks to direct the beam of light downward. 100

The solenoid 9 is of ordinary construction. The core is provided with a reduced portion which is surrounded by a non-magnetic sleeve 11. A stop 12 is carried by the core to limit the movement of the core when the solenoid is deenergized. The end of the core carries a ball 13 over which is turned one end of a tube 14. A similar ball 15 is movably carried in the opposite end of the 110 tube. A follower 16 engages each ball and a compression spring 17 between the fol-

lowers keeps the balls 13 and 15 pressed outward against the turned over ends of the tube. The shank 18 of the ball 15 is screw-threaded and extends through a perforation 5 in a lip 19 carried by the ring or annulus 6. A nut 20 engages the shank 18 and provides for adjustment of the connecting rod composed of the balls 13 and 15 and tube 14.

The end of the core opposite the stop 12 10 is provided with a head 21 and a flange 22 surrounds the core a short distance from the head.

Arranged at right angles to the solenoid 9 and near one end thereof is a locking selector 15 23 the core 24 of which is provided with a head 25 having its diameter nearly equal to the distance between the head 21 and collar 22. The inner end of the core 24 is reduced in diameter and a coil spring 26 20 bears against the core and a head on the solenoid whereby the attraction of the core will be against the compression of the spring.

An iron strap 27 of sufficient thickness and a width approximately equal to the diameter of the solenoids is bent or stamped to shape to inclose four sides of each solenoid so that iron-clad solenoids are produced. A foot 28 is formed on the strap and said foot is provided with threaded perforations 30 whereby the strap carrying the solenoids may be secured to the inside of the casing.

As shown in Fig. 4 the solenoids are, in series with a source of current 29 there being a switch 30 in the line. A shunt 31 is 35 arranged across the line and has a switch 32 therein. If desired a resistance 33 equal to the resistance of the solenoid 9 may be inserted in the shunt.

Normally the device is in the position 40 shown in full lines in Fig. 2. Both solenoids are deenergized and the core 10 will be in position with the stop 12 resting against the casing 27. The spring 26 of the locking solenoid will cause the head 25 of the core 24 45 to engage the core 10 behind the flange 22. The core 10 will, therefore be positively locked against movement in either direction and the reflector will be in position to direct the beam of light horizontally.

Upon approaching another car traveling 50 in the opposite direction the driver will close the switch 30. The current will flow from the source 29 through both solenoids 23 and 9. The core 24 will be attracted against the 55 compression of the spring 26. This will result in the unlocking of the core 10 which will be sucked into the solenoid 9 and swing the upper edge of the reflector downward. The driver will now open the switch 60 30. Both solenoids will be deenergized, the spring 26 will cause the head of the core 24 to engage between the head 21 and flange 22 of the core 10, as shown in Fig. 3, and lock the reflector in its tilted position.

When it is desired to bring the reflector

back to normal the switch 32 is closed. The current will now flow through the locking solenoid and attract its core and release the core 10 which by gravity will return to the position shown in Fig. 2 and bring the reflector to its normal, horizontal position. The switch 32 will now be opened and the spring 26 will engage the head of the core 24 in front of the flange 22 and lock the core 10 in position.

The switches 30 and 32 may be push buttons and may be located in a position convenient for the driver. They may even be placed on the steering wheel so that the car will be completely under control while passing another vehicle. This feature is of importance as when the reflector is deflected by a manual operation the driver must remove his hand from the wheel at the time he should have his machine under perfect control.

If desired a spring, such as shown at 34 in Fig. 4 may be employed to return the parts of the device to the normal position.

The construction of the connecting rod between the core 10 and the annulus 6 will hold the parts under tension and prevent rattling.

While I have shown and described my invention as applied to an automobile headlight I desire to have it understood that the device may be employed in other situations such for example as locomotive headlights. By the use of my invention it will be possible to use powerful electric headlights on railroads other than single track lines.

My invention may be employed in connection with gas lamps as well as electric lamps.

The device is extremely compact. All of the moving parts are inclosed within the casing. There are no projecting handles, levers or shafts. Each headlight is complete in itself and a breakdown in one will not affect another.

The core 24 of the solenoid 23 is, in effect, a spring bolt which is withdrawn from engagement with its co-acting parts by the passage of an electric current around it.

In accordance with the provisions of the patent statutes I have described the principle of my invention, together with the apparatus which I now consider to represent the best embodiment thereof, but I desire to have it understood that the apparatus shown is merely illustrative, and that the invention may be carried out in other ways.

Having thus described my invention what I now claim as new and desire to secure by Letters Patent, is:

1. A headlight having a pivoted reflector, a source of light in fixed relation to the focal axis of the reflector, a solenoid, a connection between the core of the solenoid and the reflector, whereby when the former is energized the focal axis of the latter will be varied, a spring bolt for locking the core in

either of its extreme positions, and a magnetic coil for withdrawing the bolt.

2. A headlight having a casing, a pivoted reflector, a source of light in fixed relation to the casing, a solenoid, a connection between the core of the solenoid and the reflector, whereby when the former is energized the focal axis of the latter will be varied, a spring bolt for locking the core in either of its extreme positions, a magnetic coil for withdrawing the bolt, all of the moving parts being inclosed within the casing, and means located outside of the casing for controlling the operation of the magnetic devices.

3. A headlight having a casing, a pivoted reflector, a source of light in fixed relation to the reflector, a solenoid, a spring cushioned connecting rod joining one end of the

core of the solenoid and the reflector, spaced enlargements at the opposite end of the core, a second solenoid at right angles to the first solenoid, whereby the core of the second solenoid will engage the enlargements to lock the first mentioned core in position, a strap surrounding the solenoids and securing them in position, said strap being secured to the inside of the casing, and manually operated means for controlling the energization of the solenoids, said control being located at a distance from the headlight.

This specification signed and witnessed this twenty-third day of August, 1917.
